UNITED STATES PATENT OFFICE.

DANIEL E. COTA, OF WALTHAM, MASSACHUSETTS.

TRAFFIC SIGNAL.

Application filed December 10, 1921. Serial No. 521,435.

To all whom it may concern:

Be it known that I, DANIEL E. COTA, a citizen of the United States, residing at Waltham, in the county of Middlesex and State of Massachusetts, have invented certain new and useful Improvements in Traffic Signals; and I do hereby declare the following to be a full, clear, and exact description of the invention, such as will enable others skilled in the art to which it appertains to make and use the same.

Drivers of motor vehicles generally signal their intention of slowing, stopping or turning by means of the hand which is extended and moved according to a prearranged code. This is satisfactory in daylight, but is not satisfactory after nightfall because the darkness precludes the hand being seen to any appreciable distance.

The present invention has for its object to render the hand visible after dark when utilized for purposes of signaling when driving a motor vehicle. In accordance with the invention, a reflector is worn upon the back of the hand or wrist, whereby to utilize rays of light to render the hand visible when signaling with the result that hand signaling after dark may be as effective as during the day.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the application,

Figure 1 is a detail view of the human hand illustrative of the invention, and having a reflector applied to the back thereof,

Figure 2 is a detailed view of a modification in which the reflector has a corrugated surface, and

Figure 3 is a sectional detail.

Corresponding and like parts are referred to in the following description and designated in the several views of the drawings by like reference characters.

In accordance with the invention, the reflector may be plain, as indicated in Figure 1, or corrugated, as illustrated in Figure 2.

The reflector may be of any material and relative size or outline so as to be conveniently and comfortably worn upon the back of the hand or wrist, as desired. The 60 numeral 1 designates the plain reflector and 2 the corrugated reflector. A suitable base 3 receives the reflector and serves as means for attaching the same to the hand or wrist. The base 3 may consist of a strap, mitten 65 or glove and the reflector may be attached thereto in any preferred way. In the present instance, the base 3 is shown as consisting of a piece of flexible material such as textile, having opposed tabs 4 which are 70 connected by an elastic web or tape 5 so as to encircle the hand or wrist and retain the device in the required adjusted position. The reflector is slightly curved between opposite edges to conform to the hand or 75 wrist so as to fit the same closely and avoid causing discomfort. The surface of the mirror is highly polished so as to reflect rays of light falling thereon, whereby to render the hand visible when extended and 80 in the act of signaling.

It is the intention that the driver of a motor vehicle wear the device upon the back of the hand or wrist after nightfall so that when the hand is extended to give a signal, 85 the same is made visible by the rays of light falling upon the reflector and projected thereby in the manipulation of the hand to render the latter visible and enable the intention of the driver to be conveyed to the 90 operator of a vehicle in the rear in substantially the same manner as practiced during the day.

What is claimed is:

A traffic signal having a base of inelastic 95 material, a reflector thereon, said reflector being curved between opposite edges to fit the hand of a user, said base including tabs integral therewith and returned from opposite edges thereof to provide substantially 100 hook shaped portions adapted to extend partly around the hand and coact therewith to prevent displacing movement of the signal transversely of the hand, and an elastic tape spanning and secured to said tabs. 105

In testimony whereof I affix my signature in presence of two witnesses.

DANIEL E. COTA
